UNITED STATES PATENT OFFICE.

VICTOR G. VAUGHAN, OF WILKINSBURG, PENNSYLVANIA, ASSIGNOR TO WESTINGHOUSE ELECTRIC & MANUFACTURING COMPANY, A CORPORATION OF PENNSYLVANIA.

ELECTRIC RADIANT HEATER.

Application filed May 24, 1923, Serial No. 641,054. Renewed August 11, 1925.

To all whom it may concern:

Be it known that I, VICTOR G. VAUGHAN, a citizen of the United States, and a resident of Wilkinsburg, in the county of Allegheny and State of Pennsylvania, have invented a new and useful Improvement in Electric Radiant Heaters, of which the following is a specification.

My invention relates to electrical heating devices and particularly to radiant electric air heaters.

One object of my invention is to provide a relatively simple and compact electrical air heater of the radiant type comprising a casing and a refractory resistor-supporting plate located therein.

Another object of my invention is to provide a radiant electric air heater comprising relatively few parts that are easily assembled and disassembled.

Another object of my invention is to provide a refractory means for supporting a plurality of radiant heating units, the refractory means having integral surfaces for reflecting the heat generated by portions of said heating units.

Another object of my invention is to provide a circuit-controlling means for permitting the energization of the heating units in such manner as to simulate the action of a gas flame of increasing capacity.

In practicing my invention, I provide an ornamental casing having a front opening therein and means for supporting a refractory electric-insulating plate in said casing adjacent said front opening in such manner that it can be easily and quickly removed therefrom and replaced therein. The plate is provided with a plurality of vertically extending rows of integral, spaced, overhanging projections that extend angularly from the face of the plate.

The projections in alternate rows extend in opposite directions and are offset relatively to each other. Integral ridges are located between the rows of projections. A portion of the angularly extending outer surface of each of the overhanging projections is of such shape as to constitute a reflecting surface for a portion of the heating unit located adjacent thereto.

A plurality of heating units are supported by the overhanging projections in a

zigzag path across the face of the plate and severally comprise a helically wound resistor wire. A plurality of bus bars are provided to permit of employing the same individual heating units on either a 110 volt or a 220 circuit.

A control switch is provided for selectively energizing the heating units to simulate the operation of a gas heater when the amount of gas permitted to be burned is increased.

In the drawings,

Figure 1 is a view, in front elevation, of an electric air heater embodying my invention,

Fig. 2 is a view, in end elevation, of a refractory resistor-supporting plate comprising a part of the device embodying my invention,

Fig. 3 is a view, in vertical section, through the heater illustrated in Fig. 1, taken on the line III—III thereof,

Fig. 4 is a schematic representation of a diagram of connections suitable for energization from a 200 volt circuit, and

Fig. 5 is a schematic representation of a diagram of connections suitable for energization from a 110 volt circuit, both diagrams of connections embodying a part of my invention.

An electric heater 11 comprises an ornamental casing 12 that may be of substantially the form and contour illustrated in Figs. 1 and 3 of the drawing. The casing 12 has a recessed front that is located between two ornamental side columns 13, and is provided with suitable supporting members 14. The casing 12 may be built up in any suitable or desired manner, either by the employment of sheet metal members or by casting the case either in its entirety or in parts and then assembling the same. The main object of this part of the device is to provide a casing having an ornamental and pleasing appearance in co-operation with the heating element to be hereinafter described more in detail.

The casing 12 is provided in its front portion with an opening 15 within which there is located a plate 16 of a refractory electric-insulating material, that constitutes the supporting means for a plurality of heating units to be hereinafter described in detail.

- Suitably recessed integral portions are provided to permit of easily and quickly inserting the plate 16 in and removing it from its proper operative position in the casing.
- 5 The front surface of the plate 16 is provided with a plurality of vertically extending rows of spaced projections 17 that extend angularly from the surface of the plate and are of substantially triangular shape.
- 10 The projections 17 in the alternate rows extend in opposite directions and are located in staggered relation. Vertically extending ridges 18 are located between the adjacent rows of projections 17.
- 15 The projections 17 are each provided with an overhanging portion 19 in order that a helically wound resistor member 21 extending along the two sides of the projections 17 of substantially triangular form, may be held in close operative engagement against the front surface of the plate immediately below the overhung portion of the respective projections 17.
- 20 The resistor members 21 extend in a zigzag form in substantially a horizontal direction across the plate 16, and are held in their proper operative position by the overhanging projections 19. As it is desired to operate the individual heating units 21, at such 25 temperature as will cause them to glow, it is desirable to so hold them as to have the smallest possible portion thereof in actual operative engagement with the plane surface of the plate and this object is accomplished by the provision of the vertically extending ridges 18. The heater units 21 are, therefore, supported by the alternately oppositely-extending overhanging projections and are prevented from operatively 30 engaging the plane surface of the plate over any extended portion of their length by the intervening ridges 18.
- 35 The front surfaces 22 of the respective projections 17 extend angularly from the surface of the plate 16 and constitute a small reflecting surface for that portion of an adjacent heating unit located immediately therebelow or thereabove, as is the case in adjacent rows of projections.
- 40 I have illustrated six independent heating units 21 that are each of such length and resistance as to permit of connecting them directly to a 110 volt circuit. When it is desired to connect them to a 220 volt circuit, 45 two of the heating units are connected in series circuit relation to each other. Figs. 4 and 5 illustrate schematically two diagrams of connections that are employed with the hereinbefore described heating units.
- 50 Fig. 4 illustrates a diagram of connection for energization from a 220 volt circuit. A bus bar 23 is mounted on the back of the plate 16 by suitable screws extending through spaced openings 24 that are located adjacent to the right-hand edge of the plate. A plu- 55 rality of bus bars 25, 26 and 27, of successively increasing length and comprising either formed bars of metal or relatively heavy conductors, are secured against the back of the plate by screws 28 extending through openings 29. The left-hand ends of each two adjacent coils are connected at the back, extending through openings 30 adjacent to the left-hand edge of the plate. The right-hand ends of the first, third and 60 fifth coils, beginning at the top, are electrically connected to the bus bar 23, extending through holes 30 adjacent the right-hand edge of the plate.
- 65 The right hand ends of the second, fourth and sixth coils extending through openings 30 are electrically connected to the bus bars or conductors 27, 26 and 25, respectively.
- 70 A control switch 31 is mounted in any suitable location on the casing 12, preferably 75 in some inconspicuous but convenient and accessible place. The end of one of two supply circuit conductors 32 is electrically connected to the bus bar 23 and the end of the other supply circuit conductor 33 is electrically 80 connected to one of the terminals 34 of the switch 31. The bus bars or conductors 25, 26 and 27 are electrically connected respectively to terminals 35, 36 and 37 of the switch. A contact bridging member (not 85 shown) is provided in the switch 31 and is effective, successive turning movements thereof, to electrically connect the terminal 34 to the terminal 35, then additionally to terminal 36 and finally additionally to terminal 37. In the first operative position of the bridging member, the lower two heating units are energized, in the next position of the bridging member, the two intermediate 90 heating units are also energized, and in the last position thereof, all of the heating units are energized. This operation of the heating units simulates very closely the operation of the ordinary radiant gas heater when the amount of gas permitted to be burned is 95 gradually increased to its maximum normal quantity.
- 100 Fig. 5 illustrates schematically a diagram of connections that is employed when the heater is to be energized from a 110 volt 105 circuit and differs in the method of connecting the individual heating units to the respective bus bars and in the location of the bus bar 23. The left-hand ends of all of the heating units 21 extend through openings 30 and are connected to the bus bar 23 that is now located adjacent to the left-hand end of the plate 16 and is connected to the supply circuit conductor 32 by a suitable 110 conductor 38.
- 115 The right-hand ends of the respective heating units 21 are connected in pairs to the respective bus bars 27, 26 and 25 beginning at the top of the heating units, substantially 120 as illustrated in Fig. 5.

When the contact bridging member of the switch 31 is moved from its inoperative position, it first connects the terminal 34 to the terminal 35 whereby the lower two heating units are energized.

Further operation of the contact bridging member effects substantially the same energization as hereinbefore described for a 220 volt supply circuit.

10 The device embodying my invention thus provides a relatively simple heating element of relatively large capacity that is located in an ornamental casing from which it may be easily and quickly removed in case of 15 necessity and within which it may be quickly and easily replaced.

The zigzag form in which the respective heating units are held, provides a pleasing 20 form therefor when the same become incandescent during the operation thereof. Substantially all of the heat generated by the heating units is dissipated by radiation, and only a small proportion thereof is dissipated by convection currents of air, but all of the 25 heat generated is effective in heating a room in which a heater of this type is placed.

The system of control comprising a part 30 of my invention is believed to be novel and effective in controlling the energization of a heater of this type to simulate the action of a gas heater of the radiant type.

Various modifications and changes may be made without departing from the spirit of the invention, and I desire, therefore, that 35 only such limitations shall be placed thereon as are imposed by the prior art, or are set forth in the appended claims.

I claim as my invention:

1. An electric heater comprising a refractory plate having a plurality of spaced, parallel and alternately oppositely extending, integral, projecting, overhung portions a resistor member extending in a zigzag path past said overhung portions and being supported thereby, and a spacing member adjacent to said overhung portions for maintaining said resistor member in spaced relation with said plate.

2. An electric heater comprising a refractory plate having a plurality of parallel rows of spaced, integral, overhung projections, the projections in adjacent rows extending in opposite directions, a resistor member supported by said integral projections and extending laterally of said rows, and a plurality of spacing members located between said rows of projections for maintaining said resistor members in spaced relation relatively to said plate.

3. An electric heater comprising a refractory plate having a plurality of spaced, integral, overhung portions, projecting angularly from said plate, a helically-wound resistor member extending between and held 65 by said overhung portions, and a spacing

member adjacent to said overhung portions for maintaining said resistor member in spaced relation relatively to said plate.

4. An electric heater comprising a resistor member and a refractory resistor-supporting plate having a plurality of spaced, integral, alternately oppositely-extending overhung portions projecting angularly from said plate, the outer surfaces of said angularly-projecting portions forming reflecting surfaces for predetermined portions of said resistor member.

5. An electric heater comprising a refractory plate having a plurality of spaced, integral, alternately oppositely-extending, overhung portions, a resilient resistor member engaged and supported by said overhung portions at spaced intervals whereby all parts of said resistor member are maintained at substantially uniform tension under all conditions of operation, and a spacing member adjacent to said overhung portions for maintaining said resistor in spaced relation relatively to said plate.

6. An electric heater comprising a refractory plate having a plurality of parallel rows of spaced, integral, overhung projections extending angularly from said plate, the projections in adjacent rows extending in opposite directions, and a resilient resistor member extending laterally of said rows and supported by said overhung projections and having a part of the heat generated thereby when suitably energized, reflected outwardly by the outer surfaces of 100 said overhung projections.

7. An electric heater comprising a casing having an opening in the front thereof, a refractory plate located in said opening and comprising a plurality of parallel rows of spaced, integral, overhung projections, the projections in adjacent rows extending in opposite directions and the projections being alined laterally of the rows, a plurality of resistor units respectively engaging and supported by said overhung projections and extending in zigzag path laterally of said rows, and a plurality of spacing members extending substantially parallel to said rows 110 to maintaining said resistor units in spaced relation relatively to said plate.

8. An electric air heater comprising a casing having an open front, a refractory plate in said open front having a plurality of horizontal rows of alternately oppositely-extending, overhung projections extending angularly from the surface of said plate, a plurality of radiant resistor units supported by the respective rows of overhung projections, and circuit-controlling means for so selectively energizing said resistor units as to simulate the action of a gas flame of increasing strength.

9. An electric air heater comprising a casing having an open front, a refractory plate

- in said open front having a plurality of horizontal rows of alternately oppositely-extending, overhung projections extending angularly from the surface of said plate, a plurality of radiant resistor units supported by the respective rows of overhung projections, and circuit-controlling means for permitting energization of increasing numbers of resistor units, beginning at the bottom and extending upwardly, in accordance with the position of said circuit-controlling means.
10. An electric air heater comprising a casing having an open front, a refractory plate in said open front having a plurality of horizontal rows of alternately oppositely-extending, overhung projections extending angularly from the surface of said plate, a plurality of radiant resistor units supported by the respective rows of overhung projections, a plurality of bus bars in said casing, a circuit-controlling means, and means for electrically connecting said resistor units, bus bars, and circuit controlling means to permit of energizing increasing numbers of 25 resistor units, beginning at the bottom and extending upwardly, in accordance with the position of said circuit-controlling means.
11. An electric air heater comprising a plurality of horizontally-extending heating units located in superposed spaced relation relatively to each other, a circuit-controlling means and connections to said heating units to permit of energizing increasing numbers of heating units, beginning at the bottom and extending upwardly, in accordance with the position of said circuit-controlling means.
12. An electric air heater comprising a plurality of horizontally-extending super- 40 posed radiant heating units, and circuit-controlling means for permitting of selectively energizing the heating units to simulate the action of a gas flame of increasing strength.
- In testimony whereof, I have hereunto 45 subscribed my name this 21st day of May 1923.

VICTOR G. VAUGHAN.
